UNITED STATES PATENT OFFICE.

GEORGE DE LAVAL, OF ORANGE, NEW JERSEY, ASSIGNOR TO T. A. GILLESPIE COMPANY, OF NEW YORK, N. Y., A CORPORATION OF DELAWARE.

DETONATING-FUSE.

1,310,742.

Specification of Letters Patent.

Patented July 22, 1919.

Application filed June 26, 1917. Serial No. 177,032.

To all whom it may concern:

Be it known that I, GEORGE DE LAVAL, a citizen of the United States, and a resident of Orange, county of Essex, State of New

5 Jersey, have invented certain new and useful Improvements in Detonating-Fuses, of which the following is a specification.

This invention relates to detonating fuses of a well-known type, in which the initial 10 explosion arises by contact between the end of a firing pin and a detonator cap.

One of the objects of the invention is to provide a mounting for the firing pin which will hold the pin in correct position while 15 the shell is in flight. Another object of the invention is to provide a mounting for a firing pin so that the pin need not be inserted until the shell is about to be used, so that any possibility of premature explosion of 20 the shell by reason of the presence of the pin is obviated.

With these and other objects in view, my invention consists of certain novel features of construction, combination and arrangement of parts, as will be more fully described and pointed out in the appended 25 claim.

In the drawings, Figure 1 is a sectional elevation of a detonating fuse of a well-known type, showing my novel mounting 30 for the firing pin; and Fig. 2 is an enlarged view of the base of the firing pin in this mounting.

Fig. 3 represents an enlarged view of the 35 end of the fuse with a modification of the mounting of the end of the firing pin.

The corresponding parts are referred to both in the drawings and in the specification by similar reference characters.

40 In the drawings 10 is the steel case of the detonator, which I have selected for purposes of illustration. Referring to the forms shown in Figs. 1 and 2, 11 is the head plug removably inserted in the case. 12 is 45 the striker rod, carrying at its lower end the cap 13. The striker rod 12 is held nor-

mally in the position shown in Fig. 1 by the stirrup 14 and the ferrule 15. A spring 16 serves also to hold the striker rod in normal position.

50 The parts so far described are of well-known construction, and no further description will be necessary.

Beneath the head plug 11 I insert a separate piece 17, which acts as a retainer or 55 mounting for the base of the firing pin 18, which extends into the bore of the striker rod 12. Preferably the member 17 has a conical opening, and the base of the firing pin is made conical to fit this opening. Also 60 preferably the firing pin projects above the surface of member 17 so as to abut against the head plug 11.

In the modification shown in Fig. 3, the head plug 21 is provided with a threaded 65 opening into which is secured the headless screw 22, the end of which forms the abutment for the firing pin 18. The opening for the screw 22 is large enough to permit the 70 passage of the firing pin.

75 With my novel construction, the detonator, complete in all respects except for the insertion of the firing pin, may be inserted in the loaded shell with the head plug 11 or 21, in place, so that the shell can be shipped without the possibility of premature explosion because of the presence of the firing pin, the firing pin being handled separately.

When the shell is to be used, the head plug 11 of Fig. 1 is unscrewed, the firing 80 pin passed through the opening in the retainer 17, and the head plug again returned to position, when it will act as an abutment for the end of the firing pin.

85 When the modification of Fig. 3 is used, the loaded shell with the head plug 21 in place, but without the firing pin, may be shipped. When the shell is to be used, the screw 22 is removed, the pin inserted, and the screw 22 returned to place.

90 Other modifications of my construction will be obvious to those skilled in the art

and I do not desire to limit my invention to the specific forms which I have chosen for purposes of illustration only.

I claim:

- 5 In an impact fuse for explosive shells, in combination, a body member having a central opening therein, a casing containing a striker rod in the opening, a casing retainer in the body member and adapted to hold the

casing in position, a firing pin removably inserted in the retaining member and a head plug removably inserted in the body member and adapted to abut against the end of the firing pin.

GEORGE DE LAVAL.
